CERAMIC GLAZED WALL TILE

Edwin F. Wanner, Pittsburgh, Pa., assignor to Natco Corporation, Pittsburgh, Pa., a corporation of Pennsylvania

Filed Nov. 27, 1962, Ser. No. 72,626

Term of patent 14 years

(Cl. D18—2)

Fig. II

Fig. I
Fig. III

FIGURE 1 is a front elevational view;
wall tile embodying my new design.

I claim:
The ornamental design for a ceramic glazed wall tile,
as shown.
